WATER TUBE BOILER

Samuel Lippincott Griswold Knox, Englewood,
N. J.

Application January 8, 1936, Serial No. 58,178

20 Claims. (Cl. 122—351)

This invention relates to improvements in water tube boilers and more particularly to a system for improving the circulation of water in the boilers.

- 5 In explanation of the various aspects of invention to be disclosed hereinafter, it will be understood that natural circulation in a water tube boiler depends on the difference in specific gravity of the water in the "ascending" or up-take and the "descending" or downtake tubes. The water in the tubes nearest the flame not only becomes the hottest, but also steam is generated most rapidly in those tubes, with the result that the mixture of steam bubbles with the 10 water makes the column of water and steam lighter and enables the weight of the water in the colder or outside tubes to force the lighter columns upward, thus creating the necessary circulation.
- 15 After the water has begun to make steam, however, there is in a boiler of the type under consideration relatively little difference in the temperature between the outer or descending column of water and the inner or ascending column of water, as the rapid circulation mixes all of the water in the boiler. The circulation under these conditions therefore depends almost entirely on the weight differential in the respective columns of water due to the difference in quantities of steam entrained in the columns. It has been previously proposed to inject feed water directly into the downtake tubes and such has beneficial effects on the circulation in that the 20 descending column of water is eliminated or reduced and at the same time the descending column of water is selectively cooled whereby its weight is increased to overbalance the weight of the rising or ascending column of water.
- 25 My invention contemplates augmenting the beneficial results of injecting feed water into the descending column of water by supplying water successively or serially to limited groups of downtake tubes so that a limited number of such 20 tubes, such as one bank of downtake tubes, is supplied with feed water to the exclusion of other groups of banks; then a following group or bank of tubes is in turn supplied with feed water; and so on, until upon the completion of a cycle each 30 bank of downtake tubes has received its charge of feed water in successive order. This arrangement has decided advantages as compared with letting all of the feed water mix with all of the downflowing water at the same moment, because 35 the concentration of all the feed water, prefer-

ably in the form of jets, into a limited number of tubes results in the jets having increased mass and velocity, thus providing improved injector action and increasing the velocity of flow in the particular bank of tubes being supplied with feed water beyond that due to differences of specific gravity alone, thereby giving increased momentum and resultant persistence of the accelerated movement to the downflowing column of water. Another beneficial effect of my above described 10 arrangement is that the injection of feed water into any given tube in greater mass at a given moment than the alternative way will act to minimize any tendency to form steam bubbles.

This improved system of feed water supply is 15 designed to give excellent circulation, but as the most rapid circulation practicable is highly desirable, because the steam output increases for a given heating surface the more rapid the circulation, and other beneficial results are also 20 thereby attained. I may also provide means by which the circulation may be further assisted, such means being used under conditions where a greater capacity of circulation is desired than that which is afforded by the natural circulation, 25 whether or not such natural circulation is assisted by the system of feed water injection described above.

Accordingly, among the objects of my invention may be noted the provision of a simple yet 30 highly efficient system for supplying feed water to a water tube boiler in such manner as to give an improvement over the natural circulation, and/or the provision of means for further assisting the circulation if and when desired, all as 35 more particularly described hereinafter.

Other features and their objects will be in part obvious from the annexed drawings and in part hereinafter indicated from the following analysis of the invention, in which reference is made to 40 the accompanying drawings illustrating an embodiment of my idea.

In the drawings—

Fig. 1 is a transverse section through a boiler of the water tube type in accordance with my 45 invention, the connections to the feed water supply pipes being shown diagrammatically;

Fig. 2 is a longitudinal section taken along lines 2—2 of Fig. 1;

Fig. 3 is a section taken along lines 3—3 of 50 Fig. 1;

Figs. 4 and 5 are detail views illustrating the arrangement of feed water supply tubes and the injector nipples in relation to the downtake tubes;

Fig. 6 is an enlarged detail in section taken through the central water drum and impeller disposed therein;

Fig. 7 is a detail in section illustrating a suggested form of connection between the outer and central water drums;

Fig. 8 is a detail view illustrating diagrammatically a preferred connection between a water supply main and the suction side of the feed water pump.

In the drawings wherein is illustrated one physical embodiment satisfying my invention, the reference characters 10 and 11 designate a pair of steam and water drums each of which is connected with a central water drum 12 by a plurality of banks of uptake tubes 13-14, 15-16, of which the banks of tubes 13-14 connect the water drum 12 with the steam and water drum 10, with the banks of tubes 15-16 connecting the water drum 12 with the steam and water drum 11. The drums 10 and 11 are also connected with the central water drum 12 by banks of downtake tubes 17-18, 19-20, of which banks of tubes 17-18 extend between the steam and water drum 10 and an outer water drum 21 which functions as a collecting header and which is connected to the central water drum 12 as by a series of connector tubes 22. Similarly, the steam and water drum 11 is connected to the central water drum 12 by the banks of tubes 19-20 through the companion outer water drum 23 connected as by tubes 24. In addition to or in substitution for the connector tubes 22, 24, the outer drums 21, 23 may be connected to water drum 12 by means of manifolds 46, 47 to be described, which extend transversely at one or both ends thereof. The boiler at its rear side may be provided with a screen of vertical uptake tubes 25 which extend directly between the central water drum 12 and the steam and water drums 10, 11, the tubes 25 on one side of the vertical center line of the boiler delivering to the steam and water drum 10 and the tubes on the other side delivering to the companion drum 11.

While in the boiler illustrated I have shown a pair of steam and water drums, with two banks of uptake tubes and two banks of downtake tubes extending between the water drum and each steam and water drum of the pair, it will be understood that this arrangement, while preferred, is capable of modification, and a greater or lesser number of banks of uptake and downtake tubes, and more or fewer drums, may be provided in accordance with my invention to satisfy individual design requirements.

Steam collecting pipes 38, 39 which function to collect steam from the steam and water drums 10, 11, respectively, are provided, suitable connection (not shown) being made between the collecting pipes and banks of superheating tubes shown partially and designated at 32, 33, a bank of such superheating tubes being disposed preferably between the banks of uptake and downtake tubes at each side of the boiler. The banks of superheating tubes are suitably baffled as by baffle plates 35, 36, and 37, 38.

In order to supply feed water to the boiler in such manner as to mix with the boiler water, I provide feed water supply pipes 40, 41, arranged in the steam and water drum 10 and like feed water supply pipes 42, 43, arranged in the drum 11, it being noted that one supply pipe may be provided for each bank or group of downtake tubes. The said feed water supply pipes 40-41, 42-43 extend longitudinally of the said drums 10,

11 and are arranged near the mouths of downtake tubes 17-18, 19-20 to deliver thereto, through nipples 45, feed water supplied to the said feed water pipes. By reference to Fig. 4, the nipples 45 are joined to the feed water supply pipes in such manner that the nipples extend along the center line of the downtake tubes or the portions of the downtake tubes immediately adjacent the drums 10 and 11 with which they communicate. The nipples are further of relatively small diameter in relation to the diameter of the downtake tubes so that the feed water issues through the nipples 45 in jet form and acts not only to supply necessary feed water to the system but also functions to draw water into said tubes from the steam and water drums 10 and 11 with an injector action, whereby to obtain circulatory effect.

By reference to Fig. 1, the downcoming water column flows to the outer water drums 21, 23, 20 and is thence delivered to the central water drum 12 through the previously described connector tubes 22, 24, and/or the manifolds 46, 47 and from the water drum 12 circulates upwardly through the uptake tubes 13-14, 15-16 to the steam and water drums 10 and 11 where steam is collected in the dry pipes 30, 31.

In order to provide an increased path of circulation between the outer water drums 21, 23 and the central water drum 12, the previously referred to manifolds 46, 47 are provided and extend transversely between the outer drums 21, 23 at one or both ends of the boiler and deliver to the central water drum 12.

Considering now the means for supplying feed water to the several feed water pipes 40-41, 42-43 and thence to the downtake tubes, such may include a multiple plunger feed pump generally designated at 50 and suitably driven from a power shaft 51. Individual connections are provided between the several pump cylinders and the several feed water supply pipes 40-41, 42-43 whereby, with the plungers delivering in timed sequence, each plunger delivers feed water to the aforesaid supply pipes successively and in pre- 45

with the greater mass of water delivered to the particular downflow tubes at a given moment, tending to kill the tendency to form steam bubbles in those tubes.

5 While the above described arrangement is designed to provide an improved or assisted circulation system, it may be under some circumstances desirable to still further, or by other means, assist the circulation, and I provide means for thus 10 assisting circulation as aforesaid. Such preferably comprises a rotary impeller or runner 60 disposed in the central water drum 12 and extending throughout the length thereof, the impeller interior receiving downflow water at both 15 ends through the end connectors 46, 47. The impeller 60 is in the nature of a hollow tube smaller than the drum 12 and is mounted on a shaft 61 suitably journaled as in the end connectors 46, 47 and driven in any suitable manner. By reference to Fig. 6, it will be seen that the impeller tube is suitably apertured throughout its length as at 65 whereby water may pass from the interior of the tube outwardly into the drum 12, the apertures being of a size and in number as 20 to distribute the flow uniformly throughout the length of the water drum 12. The impeller tube 60 is provided on its outer surface with impeller blades 66 which function on rotation of the impeller to give added pressure to the water leaving 25 30 the tube through apertures 65 thereof whereby to force water into the banks 13—14, 15—16 of uptake tubes.

It will be understood that rotation of the impeller 60 causes water from the outer drums 21, 35 23 to be drawn through the end connectors 46, 47 into the impeller tube and thence outwardly through the perforations 65, whereupon blades 66 act to force the water into the uptake tubes.

In order to direct circulation in its proper 40 paths when the impeller is installed, it is desirable to plug or substantially plug the cross connector tubes 22, 24, if such cross connector tubes are incorporated in the boiler, and such may be accomplished as by the provision of diaphragms 45 or check valves as shown in Fig. 7. Check valves 31 illustrated are of the poppet type, each seating against a seat formed in an apertured disc 68 threaded or otherwise secured in the ends of each of the cross connector tubes 22, 24, which ends may project 50 slightly into the outer water drums 21, 23. The stems 69 of the valves are each guided in spaced guide plates 70, whereby the valves seat upon the occurrence of appreciably increased water pressure on the central water drum side 55 of the valves, as would occur with the impeller running, thus to prevent reverse circulation due to impeller action. It will be understood that unless the cross connector tubes 22, 24 are plugged in the manner described, or in a manner equivalent thereto, rotation of the impeller would force water from the central water drum 12 into the outer water drums 21, 23, this being the reversal 60 of the proper direction of flow.

Natural circulation or circulation assisted only 65 by the feed water jets can take place with the impeller installed but not turning due to the provision of the apertures 65 through the impeller tubes which permit water entering the tube from the outer water drums 21, 23 through cross connectors 22, 24 and/or end connectors 46, 47 to flow 70 through holes 65 and thence into the uptake tubes. It will be understood, therefore, that when natural circulation or circulation assisted by feed water jets only is sufficient, the impeller need not be rotated, or even not installed,

but where the impeller is installed and it is desired to assist the circulation, the cross connector tubes 22, 24 are plugged or substantially plugged in the manner described, and the impeller is rotated through a suitable connection with a convenient power source.

Under certain conditions, it might be desirable to divide the volume of water directly available for an explosion should a crack develop in any drum. To provide for such an arrangement, I 10 may position in all of the drums intermediate transverse partitions 75 capable of withstanding the full pressure (see Figs. 2 and 3). Such partitions divide by two the volume of water in the boiler and neither natural nor assisted circulation would be interfered with, as the intake for the latter goes from the ends of the outer water drums 21, 23 and towards the center of the drum 12. With a partition 75 arranged in the water drum 12, the impeller would necessarily be divided into two sections 60a, 60b arranged on a common shaft 61a which extends through the partition and is journaled therein.

While in the foregoing description and accompanying drawings reference is made to drums 25 which are shown or referred to as horizontal, and to generally vertically trending uptake and down-take tubes, the principles of jet and/or impeller assisted circulation comprising the dominant features of the present invention are not limited to such an arrangement. On the other hand, such principles can be readily applied with beneficial results to boilers where the drums are vertically arranged with the tubes lying in horizontal or nearly horizontal planes, and to boilers 30 35 where the drums and/or tubes are arranged in a position intermediate the horizontal and vertical; and all such physical arrangements to which the principles of the present invention are applicable are intended to be embraced within the 40 scope of the appended claims.

It will further be understood that means for supplying feed water serially to the several banks of downtake tubes other than the multi-plunger pump may be utilized in carrying out the principles of jet assisted circulation as aforesaid. For example, a single plunger or other type of pump or injector with a distributing valve revolving at a predetermined speed could be used to produce the serial distribution of feed water to the several groups or banks of downtake tubes, and all such obvious modifications are sought and intended to be covered herein.

I claim:

1. In a water tube boiler, a steam and water drum, a water drum, at least one group of uptake tubes extending between said drums, a plurality of groups of downtake tubes extending between said drums, and means for supplying successive charges of feed water to the several groups of downtake tubes.

2. In a water tube boiler, a steam and water drum, a water drum, at least one group of uptake tubes extending between said drums, a plurality of groups of downtake tubes extending between said drums, and means for supplying feed water serially to the several groups of downtake tubes.

3. In a water tube boiler, an upper steam and water drum, a lower water drum, a water header, connections between the header and the water drum, at least one group of uptake tubes extending between said drums, a plurality of groups of downtake tubes extending between the steam and water drum and the water header, and means for 70 75

supplying feed water serially to the several groups of downtake tubes.

4. In a water tube boiler, a plurality of steam and water drums, a water drum, at least one group of uptake tubes extending between the water drum and each of said steam and water drums, a plurality of groups of downtake tubes extending between each of the steam and water drums and the water drum, and means for supplying feed water serially to the several groups of downtake tubes.

5. In a water tube boiler, a steam and water drum, outer water drums associated with said drum, a central water drum, connections between the outer and central water drums, at least one group of uptake tubes extending between the water drum and each of the steam and water drums, a plurality of groups of downtake tubes extending between said steam and water and said outer drums, and means for supplying feed water serially to the several groups of downtake tubes.

6. In a water tube boiler, a plurality of steam and water drums, outer water drums associated with the steam and water drums, a central water drum, connections between the outer and central drums, at least one group of uptake tubes extending between the water drum and each of the steam and water drums, a plurality of groups of downtake tubes extending between each of said steam and water drums and its associated outer drum, and means for so injecting feed water into said downtake tubes that circulation of water in said boiler is assisted.

7. In a water tube boiler, a steam and water drum, a water drum, at least one group of uptake tubes extending between said drums, a plurality of groups of downtake tubes extending between said drums, a multiple plunger feed water pump, and connections between said pump and downtake tubes whereby the pump delivers feed water serially to the several groups of downtake tubes.

8. In a water tube boiler, a steam and water drum, a water drum, a water header, connections between the header and the water drum, at least one group of uptake tubes between said drums, a plurality of groups of downtake tubes extending between the steam and water drum and the header, a multiple plunger feed water pump, and connections between said pump and the downtake tubes whereby the pump delivers feed water serially to the several groups of downtake tubes.

9. In a water tube boiler, a plurality of steam and water drums, outer water drums associated with said drums, a central water drum, connections between the outer and central drums, at least one group of uptake tubes extending between the central water drum and each of the steam and water drums, a plurality of groups of downtake tubes extending between each of said steam and water drums and its associated outer water drum, a multiple plunger feed water pump, and connections between said pump and downtake tubes whereby the pump delivers feed water serially to the several groups of downtake tubes.

10. In a water tube boiler, a steam and water drum, a plurality of feed water pipes disposed therein, a water drum, at least one group of uptake tubes extending between said drums, a group of downtake tubes associated with each of the feed water pipes and extending between said drums, nipples arranged on each of said feed water pipes and pointing into the tubes of an associated group of downtake tubes, and means for serially supplying feed water to the feed water

supply pipes for projection through said nipples into the several groups of downtake tubes.

11. In a water tube boiler, a plurality of steam and water drums, outer water drums associated with said drums, a central water drum, connections between the outer and central water drums, at least one group of uptake tubes extending between the central water drum and each of the steam and water drums, a plurality of groups of downtake tubes extending between each of said steam and water drums and its associated outer water drum, a feed water supply pipe in the steam and water drums for each group of downtake tubes, nipples arranged on each of said feed water pipes and pointing into the tubes of an associated group of downtake tubes, a multiple plunger feed water pump, and connections between said pump and the several feed water supply pipes for supplying feed water to said pipes serially for projection through said nipples into the several groups of downtake tubes.

12. In a water tube boiler, a steam and water drum, a water drum, at least one bank of uptake tubes extending between said drums, a plurality of banks of downtake tubes extending between said drums, means for injecting feed water serially into said groups of downtake tubes whereby to assist circulation of feed and boiler water in said boiler, and means disposed in said water drum to further assist the circulation as aforesaid.

13. In a water tube boiler, a steam and water drum, outer and central water drums, connections between the outer and central water drums, at least one bank of uptake tubes extending between said central and said steam and water drums, a plurality of banks of downtake tubes extending between said steam and said outer drums, means for injecting feed water serially into the several banks of downtake tubes whereby to assist the circulation of feed and boiler water in the boiler, and means disposed in said water drum to further assist the circulation as aforesaid.

14. In a water tube boiler, a plurality of steam and water drums, outer water drums associated with said drums, a central water drum, connections between the outer and central water drums, at least one bank of uptake tubes extending between the central water drum and each of the steam and water drums, a plurality of banks of downtake tubes extending between each of the steam and water drums and its associated outer water drum, means for injecting feed water serially into the several groups of downtake tubes whereby to assist the circulation of feed and boiler water in said boiler, and means disposed in said water drum to further assist the circulation as aforesaid.

15. In a water tube boiler, a steam and water drum, a water drum, at least one bank of uptake tubes extending between said drums, at least one bank of downtake tubes connected to said steam and water drum, a water connection between the lower ends of the downtake tubes and an end of said water drum, and means disposed in said water drum and extending substantially the length thereof, said means being operative to distribute the incoming water lengthwise of the drum and to set up a flow of water from said downtake to said uptake tubes.

16. In a water tube boiler, a steam and water drum, a water header, a water drum, at least one bank of uptake tubes extending between said water and said steam and water drums, at least one bank of downtake tubes extending between

5 said steam and water drum and said header, a tubular impeller disposed in said water drum, said impeller having perforations therein, and connections between said header and said impeller whereby water from said downtake tubes is delivered to the interior of said impeller.

17. In a water tube boiler, a steam and water drum, outer water drums associated with said drum, a central water drum, end connections between said outer and said central water drums, at least one bank of uptake tubes extending between said central and said steam and water drums, at least one bank of downtake tubes extending between said steam and water and said outer water drums, and a perforated tubular impeller disposed in said central water drum and operative to receive water through said end connections from said outer water drums and to deliver same through said perforations to said uptake tubes.

18. In a water tube boiler, a steam and water drum, a water header, a water drum, at least one bank of uptake tubes extending between said drums, at least one group of downtake tubes extending between the steam and water drum and the header, impeller means disposed in the water drum comprising a tubular runner extending substantially the length of said water drum, and end connections between said header and said runner adapted to deliver downcoming water to the interior of said runner, the runner having perfora-

tions through which the water passes into said water drum.

19. In a water tube boiler, a steam and water drum, a water header, a water drum, at least one bank of uptake tubes extending between said drums, at least one group of downtake tubes extending between said steam and water drum and said header, impeller means disposed in the water drum comprising a tubular runner extending substantially the length of said water drum, end 10 connections between said header and said runner adapted to deliver downcoming water to the interior of said runner, the runner having perforations through which the water passes into said water drum, and impeller blades carried by said 15 runner and operative to force water passing through said perforations into said upflow tubes.

20. In a water tube boiler, a steam and water drum, a water drum, uptake tubes extending between said water drum and said steam and water drum, a revolving tube arranged in and approximately coaxial with said water drum, the tube being provided with a multiplicity of apertures through which the water passes from the inside to the outside of said tube, and downtake tubes 25 from the steam and water drum communicating with the interior of said revolving tube, whereby water from the steam and water drum is supplied to the interior of said revolving tube and forced into the uptake tubes. 30
